ATTORNEY.

UNITED STATES PATENT OFFICE.

ST. CLAIR EDE, OF DUBUQUE, IOWA.

STRETCHING APPARATUS FOR HIDES.

Application filed March 18, 1925. Serial No. 16,421.

To all whom it may concern:

Be it known that I, ST. CLAIR EDE, a citizen of the United States, residing in the city and county of Dubuque and State of Iowa, have invented certain new and useful Improvements in Stretching Apparatus for Hides, of which the following is a specification.

This invention relates to a stretching apparatus for hides, and has for its object to provide, in a manner as hereinafter set forth, an apparatus of such class, having means to facilitate the stretching of and for maintaining the hide in the position to which it has 10 been stretched, and further including means for suspending the hide while held in stretched position.

A further object of the invention is to provide, in a manner as hereinafter set forth, 20 a stretching apparatus including means for suspending a plurality of hides in spaced relation while held in stretched position.

A further object of the invention is to provide, in a manner as hereinafter set forth, 25 an apparatus of the class referred to, including a stretcher frame pick-up element for suspending a stretcher frame having the hide connected thereto and held in stretched position.

A further object of the invention is to provide, in a manner as hereinafter set forth, 30 an apparatus of the class referred to, including a supporting element and a stretcher frame, and with said element and frame having co-acting means to detachably maintain the frame in horizontal and in vertical position with the hide connected thereto.

A further object of the invention is to provide, in a manner as hereinafter set forth, 35 an apparatus of the class referred to including a detachably supported stretcher frame capable of being revolved to facilitate the stretching of a hide, and further to enable the hide to be secured to both sides of the frame.

A further object of the invention is to provide, in a manner as hereinafter set forth, 40 a stretching apparatus for the purpose referred to, including means for elevating a stretcher frame, having a hide connected thereto and maintained in stretched position, to be engaged by a pick-up device for the purpose of suspending the frame.

A further object of the invention is to

provide, in a manner as hereinafter set forth, 55 an apparatus of the class referred to, including a portable frame supporting element having a series of shiftable members for removably supporting a stretcher frame in horizontal position and with said element 60 further provided with means for simultaneously shifting said members to and from supporting position with respect to the stretcher frame.

Further objects of the invention are to 65 provide, in a manner as hereinafter set forth, an apparatus of the class referred to, which is comparatively simple in its construction and arrangement, strong, durable, compact, thoroughly efficient and convenient in its 70 use, readily installed, and comparatively inexpensive to set up.

With the foregoing and other objects in view, the invention consists of the novel construction, combination and arrangement 75 of parts, as hereinafter more specifically described and illustrated in the accompanying drawings, wherein is shown an embodiment of the invention, but it is to be understood that changes, variations and modifications 80 can be resorted to which come within the scope of the claims hereunto appended.

In the drawings wherein like reference characters denote corresponding parts throughout the several views:— 85

Figure 1 is a front elevation, partly in section, of an apparatus for stretching hides, in accordance with this invention, and illustrating the stretcher frame in vertical position and arranged below the pick-up element therefor.

Figure 2 is an end elevation of the apparatus.

Figure 3 is a cross sectional view of the apparatus and illustrating the stretcher 95 frame, in full lines, in horizontally supported position, and in dotted lines in vertically elevated position in engagement with the pick-up element.

Figure 4 is a top plan view illustrating 100 the stretcher frame in horizontal supported position.

Figure 5 is a front elevation of the portable supporting element or carriage.

Figure 6 is a top plan view of the stretcher 105 frame.

Figure 7 is a section on line 7—7, Figure 6.

Figure 8 is a section on line 8—8, Figure 6.

An apparatus for stretching hides, in accordance with this invention, comprises a travelling carriage or supporting element, one or more stretching frames, one or more 5 stretcher frame pick-up devices or elements, one or more pairs of trolleys corresponding to the number of pick-up devices, a track for the carriage, and a track for the trolleys. As illustrated, there is shown but one stretcher 10 frame, one pick-up device and one trolley.

Referring to the drawings in detail, 1 denotes a set of hangers and 2 indicates another set of hangers. Preferably the hangers of one set are arranged in alignment with 15 respect to the hangers of the other set. The sets of hangers depend from a suitable support, not shown. Secured against the inner face of the set of hangers 1, by the hold-fast devices 3, is a longitudinally extending beam 4, and secured by the hold-fast devices 5 to the inner face of the hangers of the set 2 is a longitudinally extending beam 6. The set of hangers 1 is maintained in spaced relation with respect to the set of hangers 2 by brace members 7, which are mounted on 20 the top of the beams 4, 6, and these latter are permanently arranged in spaced relation. 25

Depending from the bottom of the beam 30 4 is a series of inverted yokes 8 and each of which has each arm thereof, at its lower end, provided with an inwardly extending flange 9. The flanges 9 of the arms of each yoke 8 are spaced from each other but arranged 35 in opposed relation and constitute a support for a purpose hereinafter referred to. Each of the yokes 8 is secured to the beam 4 by a hold-fast device 10.

Depending from the bottom of the beam 40 6 is a series of inverted yokes 11 and each of which has each arm thereof, at its lower end, provided with an inwardly extending flange 12. The flanges 12 of the arms of each yoke 11 are spaced from each other, but arranged 45 in opposed relation and constitute a support for a purpose hereinafter referred to. Each of the yokes 11 is secured to the beam 6 by a hold-fast device 13.

The track for the trolleys of the stretcher 50 frame pick-up device is formed from a pair of track rails supported by the yokes 8 and 11. One of the track rails is indicated at 14 and is supported by the yokes 8, and the other of the track rails is indicated at 15 55 and supported by the yokes 11. Each of the track rails consists of a longitudinally extending inverted channel iron having each side thereof, at its lower end, formed with an inwardly extending flange 16. The flanges 16 of each channel iron are arranged 60 in spaced relation but oppose each other, and the flanges of the track member 14 are supported by the flanges 9 of the yokes 8, and the flanges 16 of the track member 15 65 are supported by the flanges 12 of the yokes

11. The free ends of the flanges 9 and 12 align with the free ends of the flanges 16. The track members 14 and 15 are of less height than the yokes 8 and 11. The track members may be of any length desired.

Carrying each stretcher frame pick-up device or element, the latter constituting a suspending means for the stretcher frame, is a pair of trolleys indicated at 17, 18. The trolley 17 travels in the track member 14, and trolley 18 in the track member 15. Each trolley comprises a body portion 19, see dotted line showing in Figure 2, and to each end of the body portion 19 is connected a pair of trolley wheels 20. The pair of trolley wheels at the front of the body portion 19 is shown in full lines in Figure 1, and the pair of trolley wheels at the rear end of the body portion 19 is shown in side elevation, see dotted lines Figure 2. The trolley wheels of each pair are arranged in spaced relation. The trolley wheels travel upon the flanges 16 of the track members and are positioned in close proximity to the inner faces of the sides of the track members. When two or more pairs of trolleys are employed, one pair abutting against an adjacent pair provides in connection with the latter a spacing medium for a pair of stretcher frames when held in suspended position by a pair of pick-up devices or elements.

With reference to Figures 1, 2 and 3, the stretcher frame pick-up device or element is clearly shown, and which comprises a yoke-shaped suspension member 21 formed of a flat strip of metallic material and having one arm connected to the body portion of the trolley 17, centrally thereof, and its other arm connected to the body portion 19 of the trolley 18, centrally thereof. The arms of the suspension member 21 are indicated at 22, 23, and the former extends down between the flanges 16 of the track member 14, and the latter extends down between the flanges 16 of the track member 15. Fixedly secured to the member 21 and abutting against each of the arms thereof, is a pick-up hook 24. Each of these hooks depends a substantial distance from the member 21, and the means for fixedly securing each of the hooks to the member 21 is indicated at 25. Each of the hooks 24 is formed from a metallic strap provided at its top with a right angular extension 26, which overlaps the upper face of the base of the member 21 and is fixedly secured therewith by the hold-fast devices 25. The lower end of the member 24 is formed with an angle-shaped extension 27 of greater length than the extension 26 and which constitutes the hooking portion of the hook 24.

The travelling carriage or supporting element for the stretcher frame is best shown in Figures 1, 2, 3, 4 and 5, and which is

shifted upon the track rails 28, 29. The said carriage comprises a rectangular frame formed of a pair of end bars 30, 31, and a pair of side bars 32, 33. The bars of the frame are connected together by corner pieces 34. The bars of the frame are formed from angle irons and inverted whereby one of the arms of each of the irons will project outwardly at the upper end thereof, see 10 Figure 3.

Positioned against the lower edges of the side bars 32 and 33, as well as projecting therefrom, is a series of spaced transversely extending supporting members 35, 36, 37 and 38. The members 35 and 38 are spaced inwardly a substantial distance with respect to the end bars 31. Each of said supporting members is constructed from a metallic strip of substantial width and thickness, and comprises an intermediate yoke-shaped portion 39 and a pair of oppositely extending end portions 40, 41, which project outwardly from the upper ends of the sides of the intermediate portion 39 and further project 20 beyond the side bars 31 and 33. The end portions 40, 41 are secured to the side bars 32, 33, by short angle irons 42 secured in position by hold-fast devices 43 and 44.

Mounted on each end portion 40 and 41 30 is a rectangular bar 45. The bars 45 are of a length to extend from the supporting member 35 to the supporting member 38 and to project slightly over the intermediate portion 39. One of the bars 45 abuts against the side bar 32, and the other bar 45 against the side bar 33, see Figure 3. The bars 45 are secured to the end portions 40, 41 by the hold-fast devices 46.

Mounted upon the intermediate portions 39 of the members 35, 36, 37 and 38, and of a length to extend from the member 35 to the member 38, is a series of flat abutting bars 47, 48 and 49. The bar 48 is secured to the intermediate portions 39 by the hold-fast devices 50. Mounted on the bars 47 and 49 and abutting against the vertical parts of the intermediate portions 39, are the flat bars 51, 52, which project slightly onto the bar 48. The bars 47 and 51 are secured together by the hold-fast devices 53, and the bars 49 and 52 are secured together by the hold-fast devices 54. The bars 47, 48, 49, 51 and 52 are in the form of wooden planks, and the upper faces of the bars 51 and 52 are flush with the upper faces of the end portions 40, 41 of the members 35 to 38 inclusive.

Extending transversely with respect to the frame formed by the bars 31, 32 and 33, as well as disposed centrally with respect to said frame, is a supporting member 55, see Figure 1, and which is formed of a pair of opposed arms 56, 57, which are connected together by a curved coupling portion 58. The member 55 further includes an arm 59

which projects from the coupling portion 58 and is positioned centrally with respect to the latter. The arms 56 and 57 project outwardly with respect to the side bar 33, and the arm 59 projects rearwardly with respect 70 to the side bar 32. The supporting member 55 is formed with an intermediate yoke-shaped portion and a pair of oppositely extending end portions, or in other words the contour of the member 55 is the same as 75 either of the members 35 to 38 inclusive, in side elevation. The member 55 is arranged in alignment with respect to the members 35 to 38 inclusive, and the bars 45, 47, 48, 49, 51 and 52 are arranged in the same relation 80 with respect to the member 55 as they are arranged with respect to the members 35 to 38 inclusive. The hold fast devices 60 are employed for connecting the bars 45 to the member 55. Hold-fast devices 61 are employed for connecting the bars 47 and 51 together and to the member 55. Hold-fast devices 62 are employed for connecting the bars 49 and 52 together and to the member 55, and hold-fast devices 63 are employed 85 for connecting the bar 48 to the member 55. 90

Arranged against the side bar 33 of the frame of the carriage and projecting outwardly therefrom, is a flat protecting bar 64, provided centrally with a transverse cut-away portion 65, which provides a clearance so that access can be had to a foot tread to be hereinafter referred to. The bar 64 gradually decreasing in width from each side of said cut-away portion towards 95 each end thereof and it is secured to the members 35 to 38 inclusive by the hold-fast devices 66. The bar 64 is also secured to the arms 56, 57, of the member 55 by the hold-fast devices 67. The forward ends 100 of the members 35 to 38 inclusive are flush with the outer side edge of the bar 64. 105

Secured to each end portion of the supporting member 36 and to each end portion of the supporting member 37, is a strap 68. The straps 68 which are arranged at the forward end portions of said members 36, 37, are provided with aligning bearings 69, and the straps 68 which are arranged at the rearward end portions of the members 110 36, 37, are provided with aligning bearings 70. Mounted in the bearings 69 is a shaft 71 carrying at each end a wheel 72, and said wheels 72 travel on the track rails 28, 29. Carried by the bearings 70 is a shaft 73, 115 having each end provided with a wheel 74, and the wheels 74 travel on the track rails 28, 29. The shaft 71 and wheels 72 are arranged below the protecting bar 64, and the shaft 73 with the wheels 74 is arranged 120 rearwardly of the side bar 32 of the supporting frame of the carriage. 125

Secured to the forward end portion of each supporting member 35, 38, and each arm 56, 57 of the supporting member 55, 130

is a bearing 75, and secured to the rear end portion of each supporting member 35, 38 and 55 is a bearing 76.

Mounted in the bearings 76 is a rock shaft 77 which projects from each end of the rear bar 45 and has each end thereof provided with an upwardly extending crank arm, as indicated at 78, 79 and operating in the opening formed between the supporting members 35 and 38 and end bars 31. Connected to the crank arms 78, 79, are upstanding links 80, 81 respectively, which have their upper ends pivotally connected, as at 82, 83 respectively, to the inner ends 15 of the crank arms 84, 85 respectively, carried on one end of the crank shafts 86, 87 respectively.

Secured to the inner face of each of the end bars 31 of the carriage frame is a vertically extending channel iron which constitutes a guide for a vertically shiftable frame support. One of said guides is indicated at 88, and the other at 89. The guides 88 and 89 are disposed centrally with respect 20 to the end bars 31 and extend a substantial distance thereabove, and said guides are oppositely disposed with respect to each other and further open inwardly. Secured to the outer face of the guides 88, 89, and extending 25 transversely thereof are supporting brackets 90, 91 respectively, and each of said brackets, at each end thereof, is provided with a bearing. The bearings carried by the bracket 90 are indicated at 92, and those 30 by the bracket 91 at 93. Mounted in the bearings 92 is the crank shaft 86, and mounted in the bearings 93 is the crank shaft 87. Mounted on the crank shaft 86 is a spring controlled lever 94 provided with 35 an inwardly extending supporting lug 95. Mounted on the crank shaft 87 and arranged in alignment with the spring controlled lever arm 94, is a lever arm 96 provided with an inwardly extending 40 supporting lug 97. Formed integral with the crank arm 84 is an upstanding spring controlled lever arm 98 provided with an inwardly extending supporting lug 99, and formed integral with the crank arm 45 85 is a spring controlled up-standing lever arm 100 provided with an inwardly extending supporting lug 101. The lever arm 98 is arranged in alignment with the lever arm 100. The controlling springs for the lever 50 arms 94, 96, 98 and 100 are indicated at 102, and each of which is connected at its upper end to a lateral pin 103 carried by the lever arm with which the spring associates, and the latter has its lower end anchored to a 55 pin 104, carried by the inner face of an end bar of the frame of the carriage. The controlling springs 102 normally maintain the lever arms 94, 96, 98 and 100 at an outward 60 inclination with respect to the guides 84 and 85. The lever arms 94 and 102 extend, when 65

in normal position, in an opposite direction with respect to the lever arms 96 and 100. The lugs 95, 97, 99 and 101 provide means for supporting the stretcher frame, to be hereinafter referred to, in horizontal position, when the lever arms 94, 96, 98 and 100 are swung inwardly against the action of their controlling springs and to the position illustrated with respect to the lever arms 96 and 100, as shown in Figure 3. The 70 shafts 77, 86 and 87 connect the lever arms 94, 96, 98 and 100 together so that if any one of the lever arms is shifted inwardly, the other lever arms will be moved simultaneously therewith. By this arrangement 75 the supporting lugs are shifted synchronously to and from supporting position 80 with respect to the stretcher frame.

Mounted in the guide 88 is a vertically movable stretcher frame support 105 of a 85 length when in lowered position to depend below the supporting member 35. The support 105 is slidably connected to the guide 88 by a coupling member 106, which is secured to the upper end of the guide 88 and overlaps the member 105, and the latter is also slidably connected to the guide 88 by a strap 107, which overlaps the guide 88 and the member 105 and which is secured to the inner face of that end bar of the frame 95 of the carriage to which the guide 88 is secured.

Mounted in the guide 89 is a vertically movable stretcher frame support 108 of a 100 length when in lowered position to depend below the supporting member 38. The support 108 is slidably connected to the guide 89 by a coupling member 109, which is secured to the upper end of the guide 89 and overlaps the member 108, and the latter is also slidably connected to the guide 89 by 105 a strap 110, which overlaps the guide 89 and the member 108 and which is secured to the inner face of that end bar of the frame of the carriage to which the guide 89 is secured. 110

The upper end of the support 105, as well as the support 108 is cut away to provide a seat 111 and a pair of oppositely extending flared arms 112, and secured to the upper end of each support is a wear strap 113, which conforms in contour to the said end 115 of the support and is further secured to each side thereof, as at 114.

The supports 105 and 106 are elevated simultaneously through the medium of a 120 shifting mechanism therefor, and said mechanism includes a pair of elevating arms 115, 116. The arm 115 is carried on one end of a shaft 117, which is mounted in the bearings 75, and the arm 116 is carried on 125 the other end of the shaft 117. The arms 115, 116 are arranged between the supporting members 35 and 38 and the end bars 31 of the carriage frame. The arms 115 and 116 are angle-shaped in contour and the 130

vertical leg thereof is fixed to the shaft 117 and is of less height than the length of the horizontal leg thereof. The horizontal legs of the arms 115, 116 are arranged in the 5 path of the supports 105, 108 respectively, and said arms further constitute brakes for maintaining the carriage stationary when the supports 105, 108 are in lowered position, and when the supports are in such position 10 the said arms are forced against the bed upon which the track rails 28, 29 are arranged. The shifting mechanism further includes a lever arm 118, which is secured centrally to the shaft 117 and has its outer 15 end provided with a foot tread 119 arranged at the clearance formed by the cut-away portion 65 in the protecting bar 64. The lever arm 118 is of curved contour and normally is in the position shown in Figure 20 3 of the drawings, but when the shifting mechanism is actuated to elevate the supports 105 and 108, the lever arm 118 and the shifting arms 115 and 116 assume the position shown in dotted lines, Figure 3. The 25 shape of the arms 115, 116 is such that when the shifting mechanism is operated to elevate the supports 105, 108, the said arms will not contact with the base or floor upon which the track rails 28, 29 are secured. 30 The bar 64 acts as a protecting medium, not only for the shaft 71, but also to prevent the operator from stumbling over the lever arm 118.

The stretching frame for the hide consists 35 of two pair of end bars and the end bars of one pair are indicated 119, 120, and the end bars of the other pair at 121, 122. The bars 119, 120 are arranged in superposed spaced relation, and a similar arrangement is set 40 up with respect to the bars 121, 122. Positioned between each pair of end bars, at the inner end thereof, is the rear side bar 123 of the frame and which also constitutes a connecting bar co-acting with the pick-up device 45 for the purpose of suspending the frame, with the hide thereon, in vertical position. Arranged between the forward ends of the pair of end bars is the forward side bar 124 of the stretcher frame, and said 50 bar 124 projects beyond the forward end of the pair of end bars. The bar 123 is secured to each pair of end bars by the hold-fast devices 125, and the bar 124 is secured to each pair of end bars by the hold-fast devices 126. The bar 123 is of materially less 55 width than the width of the bar 124.

The frame furthermore includes a stationary and a shiftable inner bar 127, 128 respectively. The stationary bar 127 extends 60 between each pair of end bars and is fixedly connected thereto by the hold-fast devices 129. The bar 127 opposes and is spaced a slight distance from the bar 124. The shiftable bar 128 is arranged between the bars 65 123 and 127 and extends between the bars

of each pair of end bars. The bar 128 is provided with a pair of studs 130, 131, which extend therethrough and project from each face thereof. The stud 130 abuts against the inner side of the bars 119, 120, 70 and the stud 131 abuts against the inner side of the end bars 120, 122. The studs 130, 131 prevent lengthwise shifting of the bar 128 with respect to the bars 123, 127 and 124, or in other words, connect said bar 128 in 75 position and further act as guides therefor when said bar 128 is shifted relatively to the bars 123, 127.

The bar 128, when shifted to stretch the hide, is maintained in the position to which 80 it has been shifted, and any suitable means may be employed for such purpose, and by way of example, a holding means for the purpose set forth is illustrated as consisting of two pair of angle irons secured to the 85 outer sides of the end bars and overlapping the same. That pair of angle irons which is secured to the bars 119, 120, is indicated at 132, 133, and each of which is formed throughout with a lengthwise extending row 90 of openings 134, which register with openings 135 formed in the bars 119, 120, and through each set of registering openings is adapted to extend a holding pin 136, against which the inner side edge of the bar 128 95 abuts. That pair of the angle irons, which is secured to the bars 121, 122 is indicated at 136, 137, and each of which is formed throughout with a lengthwise extending row 100 of openings 138, which register with openings 139 formed in the bars 121, 122, and through each set of registering openings is adapted to extend a holding pin 140, against which the inner side edge of the bar 128 105 abuts.

A reinforcing yoke 141 is positioned centrally of the stretcher frame, overlaps the same, see Figure 3, and has its ends secured by the hold-fast devices 142 to the bar 124, and said yoke extends around and opposes 110 the outer edge of the side bar 123 of the frame. See Figure 3. The yoke 141 is only secured to the outer side bar 124 of the stretcher frame.

Secured to each end of the stretcher 115 frame, centrally thereof, is a casting, and the casting at one end is indicated at 143 and that at the other end at 144. Each casting has projecting laterally therefrom a polygonal-shaped spindle 145, preferably square, 120 which is mounted on a seat 111 when the frame is supported upon the travelling carriage.

A tool for shifting the bar 128 to stretch the hide is indicated at 146, and the rear side 125 bar 123 of the stretcher frame has its side edge provided with wear irons 147. The hide 148 is indicated in dotted lines in Figure 1 and is mounted on the stretcher frame to overlap the bar 124, and is detachably 130 se-

cured by fastening means, as indicated at 149, to each face of the shiftable inner bar 128. After the hide 148 has been connected to the stretcher frame and stretched through the medium of the bar 128 of the frame, the bar 128 is maintained in its adjusted position through the pins 136, 140. The stretcher frame is supported in horizontal position, see Figure 3, by the lugs 95, 97, 99 and 101 engaging under the end bars of the frame when the levers 94, 96, 98 and 100 are swung inwardly to the position shown in Figures 2 and 3 and the stretcher frame is also supported in horizontal position through the medium of the spindles 145 mounted on the seats 114. The spindles 145 in connection with the seats 114 provide means for revolvably supporting the stretcher frame with respect to the travelling carriage. When the levers 94, 96, 98 and 100 are swung outwardly, the frame is supported in a vertical position through the medium of the spindles 145 and seats 114.

It will be assumed that the hide has been secured to one side of the frame, the latter revolved and supported in a horizontal position to permit of the hide being secured and stretched the desired degree. The frame is supported on the lugs 95, 97, 99 and 101. The levers 94, 96, 98 and 100 are then moved outwardly and held in such position by the controlling springs 102, the frame can then be swung to a vertical position, as shown in Figure 1. After the frame has been swung to vertical position, the operator rocks the shaft 117, by the application of pressure to the foot tread 119, and the shaft 117 is so rocked whereby the lifting arms 115, 116 will be moved in a manner to assume the dotted line position in Figure 3, and on such movement of the lifting or shifting arms 115, 116, the supports 105 and 108 will be elevated carrying the frame, with the hide stretched thereon to the dotted line position shown in Figure 3, so that the frame can be connected to a pick-up element and shifted on the tracks 14 and 15 to the point desired.

When pressure is relieved on the foot tread 119, the arms 115, 116 assume normal position and the supports 105 and 108 lower to the position shown in Figure 1. When the carriage is being moved without the frame raising on the supports 105 and 108, there is only a few pounds weight, that of the supports themselves, bearing on the floor. Naturally the floor is more or less greasy and the elevating arms which extend under the supports are smooth so that the carriage may be moved freely without depressing the foot tread 119 to slightly elevate such arms. When a new frame is placed onto the supports 105 and 108 the weight of this frame resting largely on the supports will, in turn, press the elevating arms against the floor, thereby providing a braking effect which is

sufficient to prevent the machine from shifting while the operator is stretching the hide.

When the frames are suspended on the hangers and the supports 105 and 108 in their normal or lowered position, the machine can be freely pushed from one end of the track to the other without interfering with the suspended frames. When the frames are suspended they are in almost perfect alignment and the hooks on the hangers are placed high enough so that when the frames are in suspended position, the spindles are above the upper ends of the supports 105 and 108 so that these latter will clear the spindles when the machine is shifted.

It is thought that the many advantages of an apparatus for stretching hides, in accordance with this invention, can be readily understood, and although the preferred embodiment of the invention is as illustrated and described, yet it is to be understood that changes in the details of construction can be had which will fall within the scope of the invention as claimed.

What I claim is:

1. An apparatus for stretching hides comprising a carriage provided with a pair of vertically shiftable supports and means for elevating the same, a revolvable hide stretching frame removably mounted on and elevated by said supports, and a frame pick-up device connecting with the frame when the latter is elevated to suspend the same when clear of said supports.

2. An apparatus for stretching hides comprising a carriage provided with a pair of vertically shiftable supports and means for elevating the same, a revolvable hide stretching frame removably mounted on and elevated by said supports, a frame pick-up device connecting with the frame when the latter is elevated to suspend the same when clear of said supports, and said carriage further including simultaneously shiftable supports for detachably supporting the stretcher frame in a horizontal position.

3. An apparatus for stretching hides comprising a carriage provided with a pair of vertically shiftable supports and means for elevating the same, a revolvable hide stretching frame removably mounted on and elevated by said supports, a frame pick-up device connecting with the frame when the latter is elevated to suspend the same when clear of said supports, and said elevating means further constituting a brake for the carriage when said means is in inactive position.

4. An apparatus for stretching hides comprising a carriage provided with a pair of vertically shiftable supports and means for elevating the same, a revolvable hide stretching frame removably mounted on and elevated by said supports, a frame pick-up de-

- vice connecting with the frame when the latter is elevated to suspend the same when clear of said supports, said carriage further including simultaneously shiftable supports for detachably supporting the stretcher frame in a horizontal position, and said elevating means further constituting a brake for the carriage when said means is in inactive position.
- 10 5. An apparatus for stretching hides comprising a carriage, a revolvable hide stretching frame, said carriage including shiftable supports for detachably supporting said frame in horizontal position, said frame and carriage having coacting means for revolvably supporting said frame and further for supporting the frame in a vertical position, said carriage further provided with means for elevating the frame when the latter is in vertical position, and a portable pick-up device engageable with the frame when the latter is elevated for suspending it in vertical position when the frame is clear of the carriage.
- 15 6. An apparatus for stretching hides comprising a carriage provided with a pair of vertically shiftable supports and means for elevating the same, a revolvable hide stretching frame removably mounted on and elevated by said supports, a frame pick-up device connecting with the frame when the latter is elevated to suspend the same when clear of said supports, and a portable suspension means for said pick-up device.
- 20 7. An apparatus for stretching hides comprising a carriage provided with a pair of vertically shiftable supports and means for elevating the same, a revolvable hide stretching frame removably mounted on and elevated by said supports, a frame pick-up device connecting with the frame when the latter is elevated to suspend the same when clear of said supports, said carriage further including simultaneously shiftable supports for detachably supporting the stretcher frame in a horizontal position, and a portable suspension means for said pick-up device.
- 25 8. An apparatus for stretching hides comprising a hide stretching frame, means for supporting said frame in a vertical and in a horizontal position, means for elevating said frame when in a vertical position, and means engageable with said frame when in a vertical position for suspending it when clear of said supporting means.
- 30 9. An apparatus for stretching hides comprising a frame, supporting means therefor, a vertical guide arranged at each end of the frame, a vertically movable support mounted in each of said guides, a hide stretching frame revolvably and removably mounted on said supports, spring controlled means for detachably supporting said stretcher frame in horizontal position, means for elevating said supports carrying the stretcher frame therewith, and a pick-up device engageable with the stretcher frame when the latter is elevated for suspending the same when free of said supports.
- 35 10. An apparatus for stretching hides comprising a frame, supporting means therefor, a vertical guide arranged at each end of the frame, a vertically movable support mounted in each of said guides, a hide stretching frame revolvably and removably mounted on said supports, spring controlled means for detachably supporting said stretcher frame in horizontal position, means for elevating said supports carrying the stretcher frame therewith, a pick-up device engageable with the stretcher frame when the latter is elevated for suspending the same when free of said supports, and a portable suspension means for said pick-up device.
- 40 11. An apparatus for stretching hides comprising a hide stretching frame, means for revolvably, horizontally and vertically supporting said frame, means for elevating said frame when in a vertical position, and a pick-up device engageable with the frame when the latter is elevated to suspend the same when clear of said supporting means.
- 45 12. An apparatus for stretching hides comprising a hide stretching frame, means for revolvably, horizontally and vertically supporting said frame, means for elevating said frame when in a vertical position, a pick-up device engageable with the frame when the latter is elevated to suspend the same when clear of said supporting means, and a portable suspending means for said pick-up device.
- 50 13. An apparatus for stretching hides comprising a hide stretching frame, means for revolvably, horizontally and vertically supporting said frame, means for elevating said frame when in a vertical position, a pick-up device engageable with the frame when the latter is elevated to suspend the same when clear of said supporting means, and a portable support for said supporting means.
- 55 14. An apparatus for stretching hides comprising a hide stretching frame, means for revolvably, horizontally and vertically supporting said frame, means for elevating said frame when in a vertical position, a pick-up device engageable with the frame when the latter is elevated to suspend the same when clear of said supporting means, and a portable support for said supporting means, said means for elevating said supporting means constituting a brake for said portable support.
- 60 15. An apparatus for stretching hides comprising a hide stretching frame, means for revolvably, horizontally and vertically supporting said frame, means for elevating

said frame when in a vertical position, a pick-up device engageable with the frame when the latter is elevated to suspend the same when clear of said supporting means, 5 a portable support for said supporting means, and a portable suspending means for said pick-up device.

16. An apparatus for stretching hides comprising a hide stretching frame, means 10 for revolvably, horizontally and vertically supporting said frame, means for elevating said frame when in a vertical position, a pick-up device engageable with the frame when the latter is elevated to suspend the 15 same when clear of said supporting means, a portable support for said supporting means, said means for elevating said supporting means constituting a brake for said portable support, and a portable suspending 20 means for said pick-up device.

17. An apparatus for stretching hides comprising a hide stretching frame provided with a pair of oppositely extending spindles at its longitudinal axis, means in connection 25 with said spindles for revolvably supporting said frame and further for supporting the frame in a vertical position, a spring controlled shiftable supporting mechanism for detachably maintaining the frame in horizontal 30 position, an elevating mechanism coacting with said means for elevating the frame when supported in a vertical position, and a pick-up device engageable with one of the 35 side bars of the frame when clear of said supporting means in a vertical position.

18. An apparatus for stretching hides comprising a hide stretching frame provided with a pair of oppositely extending spindles 40 at its longitudinal axis, means in connection with said spindles for revolvably supporting said frame and further for supporting the frame in a vertical position, a spring controlled shiftable supporting mechanism for detachably maintaining the frame in horizontal 45 position, an elevating mechanism coacting with said means for elevating the frame when supported in a vertical position, a pick-up device engageable with one of the side bars of the frame when clear of said 50 supporting means in a vertical position, and a portable support for said supporting means.

19. An apparatus for stretching hides comprising a hide stretching frame provided 55 with a pair of oppositely extending spindles at its longitudinal axis, means in connection with said spindles for revolvably supporting said frame and further for supporting the frame in a vertical position, a spring controlled shiftable supporting mechanism for detachably maintaining the frame in horizontal 60 position, an elevating mechanism coacting with said means for elevating the frame when supported in a vertical position, and a pick-up device engageable with one of the 65

side bars of the frame when clear of said supporting means in a vertical position, and a portable support for said supporting means, said elevating mechanism further constituting a brake for said portable support. 70

20. An apparatus for stretching hides comprising a hide stretching frame provided with a pair of oppositely extending spindles at its longitudinal axis, means in connection 75 with said spindles for revolvably supporting said frame and further for supporting the frame in a vertical position, a spring controlled shiftable supporting mechanism for detachably maintaining the frame in horizontal position, an elevating mechanism coacting with said means for elevating the frame when supported in a vertical position, a pick-up device engageable with one of the side bars of the frame when clear of said 80 supporting means in a vertical position, and a portable suspending means for said pick-up device. 85

21. An apparatus for stretching hides comprising a hide stretching frame provided with a pair of oppositely extending spindles at its longitudinal axis, means in connection 90 with said spindles for revolvably supporting said frame and further for supporting the frame in a vertical position, a spring controlled shiftable supporting mechanism for detachably maintaining the frame in horizontal position, an elevating mechanism coacting with said means for elevating the frame when supported in a vertical position, a pick-up device engageable with one of the side bars of the frame when clear of said 95 supporting means in a vertical position, and a portable suspending means for said pick-up device. 100

22. An apparatus for stretching hides comprising a hide stretching frame provided with a pair of oppositely extending spindles at its longitudinal axis, means in connection 110 with said spindles for revolvably supporting said frame and further for supporting the frame in a vertical position, a spring controlled shiftable supporting mechanism for detachably maintaining the frame in horizontal position, an elevating mechanism coacting with said means for elevating the frame when supported in a vertical position, a pick-up device engageable with one of the side bars of the frame when clear of said 115 supporting means in a vertical position, a portable support for said supporting means, said elevating mechanism further constituting a brake for said portable support, and a portable suspending means for said pick-up device. 120

In testimony whereof, I affix my signature hereto.

ST. CLAIR EDE.
